INVENTOR.

EDWARD J. F. COLEMAN

UNITED STATES PATENT OFFICE.

EDWARD J. F. COLEMAN, OF BARRINGTON, RHODE ISLAND.

PULLEY-BLOCK

SPECIFICATION forming part of Letters Patent No. 660,364, dated October 23, 1900.

Application filed December 1, 1899. Serial No. 738,830. (No model.)

To all whom it may concern:

Be it known that I, EDWARD J. F. COLEMAN, a citizen of the United States of America, and a resident of Barrington, in the county of Bristol and State of Rhode Island, have invented certain new and useful Improvements in Pulley-Blocks, of which the following is a specification.

My invention relates to improvements in pulley-blocks; and it consists of an independent link-becket member of peculiar construction adapted to be bent around the lower tie or stud of the block-shell or frame, whereby a plain or common type of block may be readily converted into a becket-block, all as hereinafter set forth and claimed.

Becket-blocks as usually constructed have the shell portion somewhat elongated between the sheave and the bottom stud or tie which unites the two sides of the shell together, a metal thimble or grooved ferrule being loosely mounted on said tie. The object of such elongation of the shell is to provide ample space between the rope, served around the thimble, and the sheave member, so that the latter may turn freely. It is obvious that such former becket-blocks are somewhat heavier, larger, and more expensive than plain blocks, assuming, of course, that the sheaves are of the same size in both cases. In view of this fact it is usual for the block-manufacturer to employ for the becket-block a different and heavier shell than the one used for a plain block.

By means of my improvement a plain block may be readily converted into a becket-block without additional cost or practically without increasing the cost, the becket member itself being comparatively inexpensive. The becket may be attached to the shell by the manufacturer of the block, or it may be done by the purchaser, since the labor involved is simply to place the member in position around the lower tie or stud of the shell and bend its two end portions together, thus at the same time completing the link and forming the becket-eye to receive the rope.

In the accompanying drawings, Figure 1 is a front side elevation of a plain pulley-block provided with my improved link becket. Fig. 2 is a corresponding edge view of the

same, the becket member in both views being represented sectionally. Fig. 3 is a side view, in partial section, of the becket member or casting before being attached to the block; and Fig. 4 is a plan view of the same.

In the drawings, A indicates a pulley-block provided with my improved link becket B. The shell or frame *a* of the block is or may be made substantially as common and provided with the freely-turning grooved sheave or pulley *d*. As drawn, the shell is made of cast metal and consists of two parts united at top and bottom by inwardly-facing ties *a*, respectively, rivets *r*, passing centrally therethrough, serving to rigidly secure the shell together. The becket member *B* may be made of cast metal—as, for example, phosphor-bronze, &c.—or struck up from steel and then galvanized. I prefer the former, however. In such case the normal shape of the casting is substantially as represented in Fig. 3, wherein the end portions *b* are provided with elongated holes or eyes *e*, the sides thereof being beveled and well rounded, thereby not only adapting the pattern to be more readily drawn from the mold, but also forming when properly bent a smooth non-angular surface for the rope to pass through. The dotted lines in said Fig. 3 show the relation of the end portions when completely bent and shaped. The width of the becket at the center portion *b* may be increased, the thickness being proportionately decreased, thereby adapting the casting to be more readily bent around the post. The thickness of the end portions *b* of the becket considerably exceeds that of the center. This is done to increase the distance through the eye, so as to form a more serviceable seat for the rope when secured therein.

In attaching the becket the casting is first placed in position, say, as shown by dotted lines in Fig. 1, followed by bending the two end portions *b* downwardly until they are brought into close engagement with each other, at the same time pressing the center portion *b* around the tie or post *a*, the becket when thus mounted in place being supported by and adapted to swing freely on the said tie. Obviously the becket may be readily detached from the block-shell, if desired.

It will be observed that the axis of the hole

or eye e is at right angles to that of the supporting-tie a^2 , the becket-block thereby having the pulley-rope and the becket-rope in a plane common to both.

5 I would add that after the casting has been inserted and bent to form the becket the ends b thereof may be expanded, if desired, by means of a suitable mandrel forced into the opening e , thereby enlarging the eye and increasing the width of the ends. (See Fig. 2.)

I claim as my invention—

In a pulley-block, the combination of the two-part frame a , provided at the bottom with a connecting transverse tie or stud a^2 , a rivet 15 r passing through said tie and securing the frame together, and the link becket B bent

loosely around the tie, the two end portions of the becket, which are considerably thicker than the center portion, being pressed snugly together below the tie and provided with a 20 transversely-arranged eye e to receive a rope, the axis of the said eye being at right angles to that of the tie a^2 , whereby the rope, becket and pulley are adapted to move in a common plane, substantially as described. 25

Signed by me at Providence, Rhode Island, this 27th day of November, A. D. 1899.

EDWARD J. F. COLEMAN.
